UNITED STATES PATENT OFFICE.

FREDERIC CONDÉ, OF OSWEGO, NEW YORK.

DESIGN FOR A GARMENT-COLLARETTE.

49,411.

Specification for Design.

Patented July 18, 1916.

Application filed July 8, 1915. Serial No. 38,759. Term of patent 14 years.

To all whom it may concern:

Be it known that I, FREDERIC CONDÉ, a citizen of the United States, residing at Oswego, in the county of Oswego, State of New York, have invented a new, original, and ornamental Design for a Garment-Collarette, of which the following is a description, reference being had to the accompanying drawing.

My invention relates to a new and ornamental design for the collarettes of undergarments, such as shirts, union-suits, and other similar garments.

The design consists in a collarette for a garment as shown in the accompanying drawing.

Copies of this patent may be obtained for five cents each, by addressing the "Commissioner of Patents, Washington, D. C."

In the drawings, Figure 1 is a plan view of a garment collarette illustrating my design, showing also a portion of an undershirt to which the said article is applied; Fig. 2 is a sectional view, illustrating said design on the line 2—2 of Fig. 1.

I claim:

The design for a garment collarette as shown.

In testimony whereof, I affix my signature, in the presence of two witnesses.

FREDERIC CONDÉ.
